UNITED STATES PATENT OFFICE.

ARTHUR R. LAYMAN, OF DOVER, NEW HAMPSHIRE.

MULE STOP-MOTION.

1,215,039.

Specification of Letters Patent.

Patented Feb. 6, 1917.

Application filed August 27, 1913. Serial No. 786,912.

To all whom it may concern:

Be it known that I, ARTHUR R. LAYMAN, a citizen of the United States, residing at Dover, in the county of Strafford and State 5 of New Hampshire, have invented certain new and useful Improvements in Mule Stop-Motions; and I do hereby declare the following to be a full, clear, and exact description of the invention, such as will enable others skilled in the art to which it app pertains to make and use the same.

This invention comprehends improvements in stopping machines for spinning mules, and relates more particularly to a 15 safety attachment of this nature, which may be used in connection with a spinning mule of the Johnson & Bassett or Davis & Furber type.

The primary object of the invention is to 20 provide a stop-motion, which will operate when a draft rope breaks to actuate the shipper lever so as to throw the driving belt to the loose pulley, and which will also throw out the draft clutch.

25 Another and more specific object of the invention is to provide an attachment including rock shafts carrying rollers which engage the draft ropes and means for rocking said shafts when the draft ropes break, 30 whereby the shipper lever and draft clutch lever are actuated through means of suitable connections.

It is a well known fact that unless a spinning mule is instantly stopped when the 35 draft rope breaks, the ends are broken down, and very often much damage is done to the machine. My invention aims to provide automatic means for instantly stopping a 40 spinning mule when a draft rope breaks, thus preventing the ends being broken down, and the machine being damaged. The device permits a larger draft rope to be used 45 and makes it safe to run a machine at a much higher speed than is now found practicable.

With these and other objects in view as 50 will become more apparent as the description proceeds, the invention consists in certain novel features of construction, combination and arrangement of parts as will be hereinafter fully described and claimed.

For a complete understanding of my 55 invention, reference is to be had to the following description and accompanying drawings, in which

The figure is a perspective view, showing parts of a mule head with my stop-motion in position.

Referring in detail to the drawings by numerals 5 designates as an entirety the 60 frame of a spinning mule head of the Davis & Furber type. The frame supports the driving pulley 6 and a loose pulley 7, which are driven by a belt, not shown, that runs through a loop 8 secured to the upper end 65 of the shipper lever 9, said lever being pivotally secured intermediate its ends and indicated by the numeral 10. By means of this lever, the driving belt may be shifted from the driving pulley 6 to the loose pulley 7. The draft scroll 11 is secured to a shaft journaled horizontally between the uprights 12 of the frame and may be thrown into and out of operation through the medium of the draft clutch lever 13. 14 and 75 15 designate respectively the top and bottom draft ropes, which run over the scroll 11. The foregoing parts are included in the head of a spinning mule of a common type and are merely shown for the purpose of 80 illustrating the application of my stop-motion.

In carrying out my invention, I provide a rock shaft 16, which is journaled through suitable bearings 17 mounted upon the floor 85 which supports the spinning wheel. The rock shaft is disposed in a plane parallel to the planes of the shafts which support the pulleys and scroll and is formed with an offset portion 18 carrying an arm 19. The 90 arm 19 extends under the lower draft rope 15, which latter runs under a tension pulley 20. A roller 21 is loosely mounted upon an arm 19 of the rock shaft and is forced upwardly into engagement with the draft 95 rope by means of a contractile spiral spring 22 secured at one end to the laterally extending arm 23 and at the other end to the floor. A segmental member 24 in the form of a half circle is secured adjacent one end 100 of the rock shaft 16 and has secured to it a chain or other flexible connection 25. The chain extends around the segmental member under a small binder roller 26, around a guide pulley 27 and is connected to the 105 lower end of the shipper lever 9. When the bottom rope 15 breaks or slackens, the shaft 16 is rocked so as to cause the shipper lever 9 to throw the driving belt onto the loose pulley 7. It will be noted that when 110

the rope 15 holds the roller 21 into its lowered position, the chain 25 is slack so that the shipper lever may be manually operated to start or stop the mule.

5 In order that the draft clutch may be instantly thrown out so as to stop the scroll when the top rope 14 breaks, I provide means including a crank shaft 28. This shaft is journaled at one end through a bracket arm 29 secured to the frame 5 and at its other end through a bearing arm 30. The crank portion 31 of the crank shaft carries a roller 32, which is adapted to bear against the top draft rope 14 and be normally held in an elevated position. An arm 33 is secured to the crank shaft and has attached to its free end a contractile spring 34, said spring being also secured to the frame 5. An arm 35 is secured to one end of the 10 crank shaft 28 and is connected by means of a fastener 36 to the vertical connecting rod 37, which latter is secured at its lower end to the draft clutch lever 13. The upper end of the connecting rod 37 is longitudinally slotted, as indicated by the numeral 38 and the pin 36 extends through this slot. As the draft rope 14 moves from the large to the small end of the draft scroll, the shaft 28 is rocked slightly and the slot 38 permits 15 this movement taking place without disturbing the lever 13. When the draft rope 14 is tight, the offset portion 31 of the crank shaft 28 is held above the main portions of said shaft and the arm 32 extends upwardly 20 away from the frame 5. At this time the arm 35 is disposed in an essentially horizontal plane. The top rope 14, on the Davis & Furber mule is often broken at the end of the outward run of the mule, owing to the 25 draft mechanism not working properly or because of some obstruction that may prevent the machine from running far enough out so as to strike the lever that disengages the draft clutch at this point. My invention aims to provide automatic means for 30 throwing out the draft clutch at this point, preventing the rope from breaking. Should the rope 14 slacken or break, the spring 34 pulls the free end of the arm 33 toward the 35 frame 5 which causes the crank shaft 28 to rotate or rock so as to raise the free end of the arm 35. This upward movement of the arm 35 raises the connecting rod 37 which 40 operates upon the lever 13 so as to throw the draft clutch. Since the disengagement of the draft clutch allows the bottom rope 15 to slacken, the shipper lever 9 will also be actuated as previously described so as to throw the driving 45 belt to the loose pulley 7.

From the foregoing description taken in connection with the accompanying drawing, it will be apparent that I have provided a very simple, practical, and reliable stop-motion 50 for spinning mules, which will operate

when the draft rope slackens or breaks to disengage the draft clutch and actuate the shipper lever.

While I have shown and described the preferred embodiment of my invention, it will be understood that minor changes in construction combination and arrangement of parts as may be necessary to accommodate the device to mules and different designs, may be made without departing from the scope and spirit of the invention as claimed.

Having thus described my invention, I claim:

1. The combination with loose and driving pulleys, a vertically disposed shipper lever pivoted intermediate of its ends and having its upper portion arranged adjacent to the said pulleys and adapted to shift a belt from one pulley to another, a scroll draft rope, a rock shaft, disposed transversely with relation to the draft rope at one side of the same, a segmental member secured to the rock shaft, a flexible connection secured at one end to the segmental member and connected at the other end with the lower end of the shipper lever, pulleys for guiding the flexible connection intermediate the segmental member and the shipper lever whereby a rocking of the shaft will actuate the shipper lever to move a belt from the driving pulley to the loose pulley, a spring for urging the rock shaft to move the shipper lever from the driving pulley to the loose pulley, and an arm having a laterally extending pulley engaged by the lower flight or stretch of the draft rope, said arm being connected with the rock shaft and adapted to release the same to permit the spring to actuate the rock shaft when the draft rope breaks or slackens.

2. The combination with loose and driving pulleys, a vertically disposed shipper lever pivoted intermediate of its ends and provided at its upper end with a belt receiving portion, a scroll draft rope and a stop motion comprising a rock shaft having an arm provided with a laterally projecting pulley wheel extending beneath the lower flight or stretch of the draft rope, a tension pulley mounted above the lower flight or stretch of the draft rope and engaging the same adjacent to the said wheel, a segmental member secured to the rock shaft, a flexible connection attached at one end to the segmental member and connected at its other end with the lower terminal of the shipper lever, pulleys for guiding the flexible connection intermediate the segmental connection and the shipper lever whereby a rocking of the shaft will actuate the shipper lever to move a belt from a driving pulley to a loose pulley and a spring for urging the rock shaft for actuating the shipper lever when the draft rope breaks or slackens.

3. The combination of a draft rope, a crank shaft, having a crank portion provided with a pulley engaging the upper flight of the draft rope, said crank shaft
5 having an arm, a vertical rod having a slotted connection at its upper end with the said arm, a lever connected to the lower end of the said rod and designed to be connected with a clutch, and a spring connected

with the crank shaft for actuating the same 10 when the upper flight of the draft rope breaks or slackens.

In testimony whereof I affix my signature in presence of two witnesses.

ARTHUR R. LAYMAN.
